UNITED STATES PATENT OFFICE.

WILLIE DAWSON CARPENTER, OF HEARN, ASSIGNOR OF ONE-HALF TO
WILLIAM G. WADLEY, OF ALLENTOWN, LOUISIANA.

RAILROAD-GATE.

SPECIFICATION forming part of Letters Patent No. 536,601, dated April 2, 1895.

Application filed June 19, 1894. Serial No. 515,061. (No model.)

To all whom it may concern:

Be it known that I, WILLIE DAWSON CARPENTER, a citizen of the United States, residing at Hearn, in the parish of Webster and State of Louisiana, have invented a new and useful Railroad-Gate, of which the following is a specification.

My invention relates to improvements in railroad gates, and to that class thereof designed to be located at crossings to prevent cattle from wandering upon the track, and operated by the passing train.

The objects in view are to cheapen and simplify the construction of gate, to increase its efficiency and positiveness of operation.

With these and other objects in view the invention consists in certain features of construction hereinafter specified and particularly pointed out in the claims.

Referring to the drawings, Figure 1 is a cross-section of a track and its supporting ties together with a gate embodying my invention arranged thereon. Fig. 2 is a longitudinal sectional view thereof. Fig. 3 is a perspective view of a portion of the spring-tread.

Like numerals of reference indicate like parts in all the figures of the drawings.

The ties 1 support the usual rails 2, and projecting beyond the rails support pairs of posts 3 which rise therefrom and are located at the opposite sides of the track. The posts composing each pair are spaced apart and receive the outer ends of a pair of gates which extend laterally across and meet at the center of the track, resting on the rails thereof. These gates may be of any desired construction, but preferably consist of frames 4 which are oblong and covered by a suitable webbing 5 of reticulated wire. The outer, lower corners of the gates are provided with eyes 6, and through these and the pairs of posts 3 are passed transverse bearing-pins or bolts 7. Thus it will be seen the gates are capable of swinging away from each other, and beyond the posts so as to permit of the passage of the train.

In order to prevent undue jarring and injury to the gates by reason of their impact upon the ties I locate in cavities 9 in line with the gates and with which each tie is provided buffers 10, between whose lower ends and the

bottoms of the cavities, coiled springs 11 are seated. Each buffer is slotted, as indicated at 12, and passing transversely through the slot and engaging the wall of each cavity, is a limiting pin or bolt 13 which retains the buffer in position and permits the spring to force the same yieldingly above the surface of the tie.

The tie below the track is at each side of the same provided with a chamber 14, and the ends of the chamber are provided with vertical openings 15 and 16. A lever 17 is pivoted between its ends at 18 in each chamber and terminates at its ends below the passages 15 and 16. Links 19 are pivotally connected at 20 to the outer ends of the levers 17 and at their upper ends are pivotally connected at 21 to the lower bars of the gate.

Secured at their opposite ends to the inner sides or webs of the rails 2 at opposite sides of the gate are arched spring-treads 22, consisting of resilient bars which at their centers are provided with depressed or U-shaped portions 23, in which the lower edges of the gates are seated. These depending portions or bends 23 are loosely connected to the upper ends of links 24 whose lower ends are in turn pivotally connected at 25 to the inner ends of the levers 17. The spring-treads at opposite sides of their centers and adjacent to their outer ends, which are securely bolted as at 26 to the rails of the track, are given quarter-twists as indicated at 27, forming flattened portions 28 to receive the wheels of the train. The spring-treads, it will be seen are arched, and are designed to be depressed by the wheels of the train as the same pass thereover. The treads are connected by means of U-shaped connecting-bars or yokes 29 which extend under the rails so that should the mechanism of one gate become broken the tread at the opposite side of the track will be operated and will communicate its motion to the opposite tread, and thus cause a similar operation at each side of the track.

The operation of the gate is as follows:—A train approaching in either direction causes a depression of the spring-treads, which forces the links 24 downward depressing the inner ends of the levers 17 and consequently elevating the outer ends thereof. This causes

the gates to swing away from each other on the pivots 7 and fall back upon the buffers 10, where the jar of their impact is absorbed. As soon as the wheels of the train leave the 5 spring-treads the latter by their resiliency rise or return to their normal positions and consequently draw upward upon the links 24 and draw downward through the medium of the levers 17 upon the links 19 causing the 10 gates to close automatically in rear of the receding train.

From the foregoing description in connection with the accompanying drawings, it will be seen that I have provided a very simple 15 and cheap railroad gate, which is positively and promptly actuated by the moving train approaching the same, and which will automatically close after the receding train.

Having described my invention, what I 20 claim is—

1. The combination with a gate and its pivotal support, of the rails, the bowed spring-tread secured to a rail, the lever pivoted between its ends below the gate, and links pivotally connected to the ends of the lever, the 25 upper end of the outer link being connected to the gate and that of the inner link to the tread, substantially as specified.

2. The combination with the rails of the 30 opposite gates pivoted at their outer lower corners, the levers pivoted between their ends below the gates, the spring-treads secured to

the rails above the inner ends of the levers, and the links pivotally connected to the ends of the levers, the upper ends of the inner links 35 being connected to the treads and those of the outer links being pivotally connected to the gates, substantially as specified.

3. The combination of the gate pivoted at one side of the track, the tread consisting of 40 an arched resilient bar, secured at its ends to a rail and provided with a central, integral depending U-shaped bend, and a system of levers extending from the tread to the gate and connected with the depending bend, substantially as described.

4. The combination with the track, the opposite arched treads consisting of resilient bars secured to the rails and provided with central depending bends, the opposite posts, 50 the gates pivoted to the lower outer corners of the posts, connections between the bends of the treads and the gates, whereby a depression of the former will cause an oscillation of the latter, and the yoke bars 29 passing under the track and connecting the treads, 55 substantially as described.

In testimony that I claim the foregoing as my own I have hereto affixed my signature in the presence of two witnesses.

WILLIE DAWSON CARPENTER.
